US00D838680S

(12) **United States Design Patent** (10) **Patent No.:** **US D838,680 S**
(45) **Date of Patent:** **** Jan. 22, 2019**

(54) **MODULAR ELECTRONIC DEVICE**

(71) Applicants: **Microuino Inc.**, Westlake Village, CA (US); **Meike Technology (Beijing) Ltd.**, Beijing (CN)

(72) Inventors: **Zhenshan Wang**, Oak Park, CA (US); **Kejia Pan**, Oak Park, CA (US); **Bin Feng**, Oak Park, CA (US)

(73) Assignees: **MICRODUINO INC.**, Westlake Village, CA (US); **MEIKE TECHNOLOGY (BEIJING) LTD.**, Beijing (CN)

(**) Term: **15 Years**

(21) Appl. No.: **29/536,825**

(22) Filed: **Aug. 19, 2015**

Related U.S. Application Data

(63) Continuation of application No. 14/721,341, filed on May 26, 2015, now Pat. No. 9,801,300.

(30) **Foreign Application Priority Data**

Feb. 20, 2015 (CN) 2015 1 0085854

(57) **CLAIM**

The ornamental design for a modular electronic device, as shown and described.

DESCRIPTION

FIG. 1 is a top perspective view of a modular electronic device in accordance with the present invention;

FIG. 2 is a bottom perspective view of the modular electronic device shown in FIG. 1;

FIG. 3 is a top view of the modular electronic device shown in FIG. 1;

FIG. 4 is a bottom view of the modular electronic device shown in FIG. 1;

FIG. 5 is a left side view of the modular electronic device shown in FIG. 1;

FIG. 6 is a right side view of the modular electronic device shown in FIG. 1;

FIG. 7 is a front view of the modular electronic device shown in FIG. 1; and,

FIG. 8 is a back view of the modular electronic device shown in FIG. 1.

1 Claim, 4 Drawing Sheets
